CROSS-REFERENCE TO RELATED APPLICATIONS

This application claims priority to and the benefit of Switzerland Plant Breeders Rights application filed on Jun. 3, 2015, Application No. 15-3015, the entire contents of which are incorporated herein by reference for all purposes.

An application with the European Community Plant Variety Office was filed on Jul. 1, 2015, File No. 2015-1526.

BACKGROUND OF THE NEW PLANT

The present invention comprises a new and distinct variety of *pelargonium*, botanically known as *Pelargonium zonale* and hereinafter referred to by the variety name 'KLEPZ15403'. 'KLEPZ15403' originated from a cross-combination in June 2010 in Stuttgart, Germany between the female *pelargonium* variety 'PZ-2006-0158' (unpatented) and the proprietary male *pelargonium* variety 'PZ-2007-0004' (unpatented).

Seeds from the cross-combination in June 2010 in Stuttgart, Germany were obtained. The seeds were sown and plants were grown for evaluation. A single plant was selected in June 2011 and subsequently named 'KLEPZ15403'. In September 2011 'KLEPZ15403' was first vegetatively propagated in Stuttgart, Germany by veg-

2

etative cuttings from stems. 'KLEPZ15403' was found to reproduce true to type in successive generations of asexual propagation via vegetative cuttings in Stuttgart, Germany.

SUMMARY

The following are the most outstanding and distinguishing characteristics of this new variety when grown under normal horticultural practices in Stuttgart, Germany.

1. Pink purple flowers with a purple red eye; and
2. An upright growth habit.

DESCRIPTION OF THE PHOTOGRAPH

15 This new *pelargonium* plant is illustrated by the accompanying photograph which shows an overall view of the plant. The photograph is of an approximately ten-week-old plant grown in Stuttgart, Germany under greenhouse conditions in May 2014. The colors shown are as true as can be 20 reasonably obtained by conventional photographic procedures.

DESCRIPTION OF THE NEW VARIETY

25 The following detailed descriptions set forth the distinctive characteristics of 'KLEPZ15403'. The data which define these characteristics were collected from asexual reproductions carried out in Stuttgart, Germany. Data was collected on plants grown 2 and a half-months after planting

in Stuttgart, Germany under greenhouse conditions in June 2015. Color references are to The R.H.S. Colour Chart of The Royal Horticultural Society of London (R.H.S.), 5th edition (2007).
